ALFRED HEALD, OF PHILADELPHIA, PENNSYLVANIA, ASSIGNOR TO
McCALLUM, CREASE & SLOAN, OF SAME PLACE.

DESIGN FOR CARPET.

Specification forming part of Design No. 6,654, dated May 20, 1873; application filed April 24, 1873.

To all whom it may concern:

Be it known that I, ALFRED HEALD, of Philadelphia, Pennsylvania, have invented a Design for Carpet-Pattern, of which the following is a specification:

The nature of my design is fully shown in the accompanying photographic illustration. It consists of a series of square or diamond-shaped members, A, separated by bands or ribbons B, crossing each other at right angles, as shown, there being in the center of each member A an octagonal figure, D, and the whole pattern being ornamented in a manner

too clearly shown in the drawing to need description.

Irrespective of the colors employed, I claim—

The design for a carpet-pattern, substantially as described, and as shown in the accompanying drawing.

In testimony whereof I have signed my name to this specification in the presence of two subscribing witnesses.

ALFRED HEALD.
